UNITED STATES PATENT OFFICE.

MABLE BROWN, OF RATON, TERRITORY OF NEW MEXICO.

MATTRESS.

No. 912,536.

Specification of Letters Patent.

Patented Feb. 16, 1909.

Application filed January 2, 1908. Serial No. 408,920.

To all whom it may concern:

Be it known that I, MABLE BROWN, a citizen of the United States, residing at Raton, in the county of Colfax and Territory of New Mexico, have invented certain new and useful Improvements in Mattresses, of which the following is a specification, reference being had to the accompanying drawings.

My invention relates to improvements in mattresses and more particularly to a handle therefor.

One object of the invention is to provide the sides and ends of a mattress with improved handles whereby it may be conveniently lifted and carried while either flat or rolled into a compact bundle.

Another object of the invention is to provide an improved handle for a mattress or the like with a hand grip which may be readily detached.

With the above and other objects in view the invention consists of the novel features of construction and the combination and arrangement of parts hereinafter described and claimed, and illustrated in the accompanying drawings, in which—

Figure 1 is a perspective view of a mattress provided with my improved handles; Fig. 2 is a detail edge view of a portion of the mattress showing one of the improved handles in elevation; Fig. 3 is a horizontal section taken on the plane indicated by the line 3—3 in Fig. 2; and Fig. 4 is a detail perspective view of a modified form of the handle.

In the drawings 1 denotes a bed mattress of any suitable form and construction and having a covering 2 and a filling 3; and 4 denotes one of my improved handles. The latter are arranged upon the side and end edges of the mattress at opposite points and two of them are preferably provided upon each edge at suitable distances from the corners. By arranging the handles in this manner it will be seen that two persons, one upon either side or end of the mattress, may conveniently grasp the handles at such side or end and readily lift and carry the mattress; and that the latter may be readily folded over upon itself and the opposing handles tied together by a cord or the like to make a compact bundle of the mattress when it is desired to move or transport the same. Each of the handles 4 comprises a removable hand grip 5 which is detachably engaged with eyes 6 fixed upon the mattress. As shown in Figs.

1, 2 and 3 of the drawings the eyes or loops 6 are in the form of split pins formed by bending pieces of heavy wire or metal rods to provide loops and parallel prongs 7. These prongs 7 are passed through the covering or 60 casing 2 of the mattress and also through registering apertures formed in reinforcing strips 8, 9 arranged upon the inner and outer faces of the covering 2 as more clearly shown in Fig. 3. The strips 8, 9 may be in the 65 form of metal plates or they may be made of leather or other heavy sheet material and the pins or prongs 7 are retained in them by bending the extremities of said pins or prongs outwardly in opposite directions as shown 70 at 10. The hand grip 5 is formed from a single piece of resilient wire by bending the same at its center to provide a substantially semi-circular handle proper 11, then bending its intermediate portion to provide longi- 75 tudinally extending cylindrical coils 12 and finally bending its ends inwardly to provide opposing U-shaped hooks 13 which are adapted to engage the loops or eyes 6. By providing the hand grip with the coils 12, 80 the hooks 13 at its ends may be pulled apart to permit them to be readily engaged with or disengaged from the eyes 6.

In the embodiment of the invention illustrated in Fig. 4 of the drawings the fixed 85 eyes upon the mattress are in the form of straps 6^a of leather or the like bowed and stitched at their opposite edges as at 6^b upon the edge of the mattress; and the hand grip 5^a instead of having two coils has a single 90 centrally arranged cylindrical coil 14 which also forms the handle proper. The hooks 13' of this hand grip are formed by bending the ends of the wire of which the coil is constructed and they may be readily drawn 95 apart to permit of their insertion in or removal from the eyes or loops 6^a by extending said coil.

While my improved handles are especially designed for use upon mattresses it will be 100 understood that they may be applied to other objects which are inconvenient to lift and carry.

Having thus described my invention what I claim is:

The combination with a mattress having spaced loops or eyes thereon, of a handle formed from a single piece of resilient wire by bending the same at its center to provide the curved hand grip 11 and bending its ends 110

to provide the U-shaped hooks 13, the intermediate portion of the wire being bent to provide the coils 12 at each end of the hand grip, whereby the handle is extensible longitudinally to permit said hooks to be engaged with and disengaged from the eyes or loops on the mattress.

In testimony whereof I hereunto affix my signature in the presence of two witnesses.

MABLE BROWN.
